(57) **CLAIM**

The ornamental design for a light emitting diode, as shown and described.

DESCRIPTION

FIG. 1 is a top view of the light emitting diode of the present design.

FIG. 2 is a front elevation view of a first embodiment of the design of FIG. 1.

FIG. 3 is a side elevation view of the first embodiment of the design of FIG. 1.

FIG. 4 is a front elevation view of a second embodiment of the design of FIG. 1.

FIG. 5 is a side elevation view of the second embodiment of the design of FIG. 1.

FIG. 6 is a bottom view of the design of FIG. 1.

FIG. 7 is a perspective view of the first embodiment of the design of FIG. 1; and,

FIG. 8 is a perspective view of the second embodiment of the design of FIG. 1.
